(57) **CLAIM**

The ornamental design for shelf dispensing unit, as shown and described.

DESCRIPTION

FIG. 1 is a perspective view of a first embodiment of the design;

FIG. 2 is a front view of the design of FIG. 1;

FIG. 3 is a back view of the design of FIG. 1;

FIG. 4 is a first side view of the design of FIG. 1;

FIG. 5 is a second side view of the design of FIG. 1; and, FIG. 6 is a top view of the design of FIG. 1.

In the drawings, the broken lines depict environmental subject matter only and form no part of the claimed design.
